UNITED STATES PATENT OFFICE.

ERNEST C. DES ENFANTS, OF CHICAGO, ILLINOIS, ASSIGNOR TO J. B. CARROLL COMPANY, OF CHICAGO, ILLINOIS, A CORPORATION OF ILLINOIS.

TOY COMPUTING DEVICE AND NUMBER-REVEALING GAME.

Application filed August 9, 1926. Serial No. 128,166.

This invention relates to computing devices or number-finding and revealing games in which a sheet, card or tablet, or similar stationary member is provided, having a 5 series of correlated groups or columns of numbers thereon, and having one or more movable or rotative members adapted to be employed in the operation, trick or game of finding and disclosing, or revealing a 10 number which corresponds or is identical with any predetermined corresponding selected number contained in such series of correlated groups of numbers and which may be selected as the number to be found 15 and disclosed, or the equivalent of which is to be found and disclosed or revealed.

The principal object of the invention is to provide a simple, economical, compact and efficient computing device, or number-finding and revealing game adapted to be used 20 for finding and disclosing the age of a person whose age may be unknown to the operator, and more particularly to provide such a device which is light and compact and 25 adapted to be readily and conveniently enclosed in an envelope and transported by mail, or otherwise, and which is suitable for use as an advertising novelty, or for advertising or other purposes.

30 Other and further objects of the invention will appear from the following description and claims, and from an inspection of the accompanying drawings, which are made a part hereof.

35 The invention consists in the features, combinations, and elements, and in the construction and arrangement of parts herein described and claimed.

In the accompanying drawings—

40 Figure 1 is a view in front elevation of a device constructed and adapted to operate in accordance with my invention;

45 Fig. 2 is a view in rear elevation showing the back of the device illustrated in Fig. 1, and with a number on each of the rotative number wheels shown in exposed or reading position, the other nine numbers on each of said wheels being shown in dotted lines;

50 Fig. 3 is a view in side elevation, or edge view, of the device shown in Figs. 1 and 2; and

55 Fig. 4 is an enlarged view in transverse section, taken on line 4—4 of Fig. 2, looking in the direction indicated by the arrows.

In constructing an improved computing

device, or number ascertaining and revealing game and device for playing the same, in accordance with my invention, I provide a sheet, card or tablet 1, which is, by preference, formed of cardboard, or other suitable sheet material, and may consist of a sheet which is bent to form two leaves, such for example, as a front sheet, leaf or tablet 2, and a back leaf 3. The front and back leaves may be connected at one margin 4, if 60 desired, and folded along the said margin so that the front and back leaves are flexibly connected and formed in one integral piece, and provided with a space 5 therebetween. The opposite extremities of the front and 65 back leaves 2 and 3 are, by preference, connected by means of one or more pivots or eyelets 6, 6, which may be formed of metal or other suitable material, each of said eyelets being flanged at its opposite ends, so 70 as to hold the leaves 2 and 3 through which the eyelets extend, in position. The eyelets 6, 6, also serve as supporting pins or axles for rotatively supporting a pair of computing or number wheels or disks 7 and 8 which 75 are rotatively mounted on said eyelets 6, 6, between the front and back leaves 2 and 3. 80

Each of the rotative wheels or disks 7 and 8 is located between and adapted to project 85 outward beyond opposite curved marginal portions of the front and back leaves 2 and 3. The wheel 7 is located between a curved marginal portion or rounded corner 9 of the front leaf 2 and a similarly curved or rounded corner marginal portion 10 of the back 90 leaf 3. And the wheel 8 is located and adapted to rotate between a curved or rounded corner marginal portion 11 of the front leaf 2 and the opposed rounded corner marginal portion 12 of the back leaf 3. 95

The rotative wheels or disks 7 and 8 are each provided with a series of peripheral marginal notches 13, by preference, ten of said notches for each wheel, all of said notches being equally spaced apart and provided 100 with corresponding peripheral shoulders 14, ten in number for each wheel, between said notches or peripheral recesses 13. The peripherally notched and shouldered margins of the wheels 7 and 8 are thus adapted to 105 project outward beyond the outer curved corner marginal portions 9 and 10, and 11 and 12, into position to permit the end of the finger or finger nail of the operator to be inserted in said notches respectively, in 110

any desired order, in the operation of turning the wheel or wheels and stopping them as required. And marginal notches or recesses 15 and 16 are provided in the opposite 5 side edges of the front leaf 2 and back leaf 3 at the lower outer extremities of the curved or rounded corner marginal portions 9, 10, 11 and 12 respectively, and are adapted to engage and serve as stops for stopping the 10 finger of the operator in position to cause the adjacent computing wheel or disk to stop in proper position as required, whenever the wheel or wheels are rotated or partially rotated intermittently or in a step- 15 by-step manner in the operation of the device.

The sheet, card or tablet 1 is provided with a series of correlated groups or columns of numbers 17, 18, 19, 20, 21, 22, 23, 24, of 20 which there may be any desired number. In the form of the device shown in the drawings there are eight groups or columns; and they are each provided with an individual distinguishing mark or letter at the top of 25 each group or column respectively, for example, "A", "B", "C", "D", "E", "F", "G" and "H", in predetermined order.

The curved or rounded corner marginal portion 9 of the front leaf 2 or tablet is 30 provided with a series of equally spaced marginal graduation marks 17', 18', 19', and 20', each having an individual distinguishing mark or character, for example "A", "B", "C", and "D", in their order, corresponding with columns or groups of numbers having like individual distinguishing marks or letters as above described.

The curved or rounded corner marginal portion or segment 11 of the front leaf 2 40 or tablet 1, has a similar series of equally spaced marginal graduation marks 21', 22', 23', and 24', each having an individual distinguishing mark or character which is, by preference a duplicate of and corresponds 45 with a like distinguishing mark or character of a corresponding column or group, for example, "E", "F", "G", and "H", in the order shown in the drawing.

Each of the rotative computing or number 50 wheels 7 and 8 has a series of numbers thereon, said numbers being, by preference, on the backs of the wheels and facing toward and adapted to be normally covered and concealed by the back leaf 3, each of said 55 numbers being adjacent to and corresponding with a peripheral notch 13, or a peripheral projection 14 on the same wheel.

The series of numbers on the wheel or disk 60 7 is indicated by the reference number 25; and the series of numbers on wheel 8, by the reference number 26. Each of said series of numbers 25 and 26 includes, by preference, the ten digits "1", "2", "3", "4", "5", "6", "7", "8", "9", "0", arranged in a circle 65 in consecutive numerical order.

The back leaf 3 has an opening 27 therein across which the numbers contained in the series 25 on wheel 7 are adapted to move as said wheel is rotated intermittently, or in a step-by-step manner, said opening being rotated at the reading position for said numbers, and adapted to uncover and expose any number in said series which is moved to and permitted to stop within said opening, and particularly any number which is to be 70 read or ascertained and revealed, for example, the number "9", as shown in Fig. 2. A similar opening 28 through the back leaf 3 is formed adjacent to the opening 27; and across this opening 28 the numbers contained in the series of numbers 26 are adapted to move in successive order as the wheel 8 is rotated intermittently or in a step-by-step manner, said opening 28 being located at and adapted to indicate the reading position for said numbers on wheel 8, and being adapted to uncover and expose any number in said series in the order in which it is moved to and permitted to stop within said opening, and particularly any number which is to be 75 read or ascertained and revealed, for example, the number "5" as shown in Fig. 2.

The series of numbers on the movable members or wheels 7 and 8, and the groups or columns of numbers on the stationary member or tablet, as well as the identifying letters or characters at the tops of the groups, and the corresponding letters and graduation marks on the front leaf 2 of the tablet 1, are correlated, although the extent and character of the relations of these various elements, and particularly the relation of the movable numbers on the rotative wheels to the groups of stationary numbers and characters, and to the individual numbers in said groups is not so obvious and is not intended to be so obvious as to be readily recognized and understood upon a mere superficial inspection or without giving the matter some consideration. It is believed, however, that a brief explanation of the game and of the device and its operation will enable the invention and the relation of said elements to be readily understood.

The rotative wheel 7 and the numbers thereon are related to all of the groups or columns of numbers on the stationary sheet or tablet 1, but more particularly to the four groups or columns which are identified by the letters "A," "B," "C" and "D," respectively, and which constitute one series of groups or columns.

The numbers 1, 2, 3, and 4, on the rotative wheel 7 may be considered as constituting individual group-distinguishing title numbers by which said four groups constituting said series are individually represented and numbered in consecutive numerical order which, in the form of the device here shown.

corresponds with the alphabetical order and relative positions of said groups so numbered although the relative positions of the groups and of the characters and marks on the stationary member or tablet may be changed or arranged in any desired order provided each stationary group or column of numbers is correctly represented by its proper title number or movable number on the proper computing wheel.

The movable computing member or rotative number wheel 8 and the series of numbers thereon are related to all of the groups or columns of numbers on the stationary tablet 1, or front leaf 2 of said tablet, but more particularly to the four groups or columns which are distinguished from each other or identified by the letters "E," "F," "G" and "H," respectively, and which constitute another or second series of four correlated groups or columns of numbers which contain two-digit numbers but no single-digit numbers, the single digits on the tablet or stationary member 1 being contained only in the four groups or columns belonging to the series above described as particularly related to the computing wheel 7.

The numbers 1, 2, 3 and 4 on the movable member or rotative computing wheel 8 constitute individual group-distinguishing numbers or title numbers by which said four groups constituting said second series of groups lettered "E," "F," "G" and "H," are individually represented and distinguished from each other and numbered in consecutive numerical order. The numerical order in this instance corresponds with the alphabetical order and relative positions of said groups; but the alphabetical order and relative positions of the groups on the tablet may be altered or arranged as desired, provided the correct relation of the movable group-distinguishing or title numbers on the movable or rotative computing wheel or wheels with respect to the groups which the title numbers represent is preserved.

The correlated groups or columns of numbers on the stationary member or tablet 1 include, by preference, all of the numbers from "1" to "99" inclusive, some of which are contained in one group or column only, and others of which are contained in each of a plurality of said groups or columns. And the series of numbers on the wheels 7 and 8 may or may not contain numbers which numerically distinguish or represent the related groups of numbers, or the numerical order of arrangement of said groups; but it is believed that the invention and the operation of the device can be more readily and clearly explained and understood by considering the groups or columns on the tablet as being represented, theoretically if not actually, by corresponding numbers on said wheels, as above indicated.

The first four correlated groups, lettered "A," "B," "C" and "D," respectively contain all of the single digits or single-digit numbers, and some of the two-digit numbers; and the second series of four groups, lettered "E," "F," "G" and "H," respectively, contain two-digit numbers only, the lowest number being "10," and the highest being, by preference, "99," although less than ninety-nine numbers may, of course, be employed if desired.

The rotative computing wheel 7 is the "units" wheel, and the ten movable numbers or digits thereon are of the "units" denomination, and are to be so computed and read when moved to and stopped in reading position within the opening 27 in the back leaf 3, which is units place or reading position for numbers of the "units" denomination.

The rotative computing wheel 8 is the "tens" wheel, and the ten movable digits thereon are of the "tens" denomination, and are to be so computed, and read when moved to and stopped in reading position within the opening 28 in said back leaf, which is "tens" place, or reading position for numbers of the "tens" denomination.

Each single-digit number in the correlated groups or columns of numbers on the stationary member or tablet 1 is contained in a group or in each of a plurality of groups or columns the corresponding numbers or group-distinguishing numbers for which, when added together, will produce or equal that number, and in no other group or column. And every such number so to be found or produced and revealed in reading position within the opening 27 in leaf 3, which is "units" place or reading position for numbers of the "units" denomination, is 100 on and movable with the computing wheel 7 to and from reading position.

Each and every "two-digit" number or "plural-digit" number in said correlated groups or columns of numbers on the stationary member or tablet 1 is contained in a group or in each of a plurality of said groups or columns the corresponding numbers or group-distinguishing title numbers for which, when added together, units to units upon the "units" wheel 7, to be exposed in reading position in "units" opening 27, and tens to tens, upon the "tens" wheel 8, to be exposed in reading position in "tens" place within the "tens" opening in the back leaf 3—will produce or equal that "two-digit" number, and in no other group or column. And every such number so to be produced, or which is to be selected and found, or ascertained and revealed and which contains 115 a plurality of digits, has one of the "units" denomination, and the other of the "tens" denomination, the digit of "units" denomination being on the "units" computing wheel 7, and the digit of the "tens" denom- 130

nation being, by preference, on the rotative computing wheel or "tens" wheel 8.

The device is adapted and intended for use in playing a game, or one or more games or tricks, such, for example, as that of finding and disclosing or revealing any selected number contained in the correlated groups of numbers on the tablet and known to the person selecting such number, but unknown to the operator, or finding and disclosing or revealing the age of a person whose age is unknown to the operator, which selected numbers are to be found and disclosed by or with the aid of mechanical means, for example, by adding numbers on the rotative computing wheel or wheels which represent or correspond with the title numbers or group-distinguishing numbers of the group or groups or columns in which such selected numbers are contained.

In operation, any desired number contained in the series of correlated groups or columns of numbers on the tablet, is selected as the number to be found and disclosed by the operator, such, for example, as the number representing the age of the person who selects such number and which may be unknown to the operator.

The person whose age is to be found and disclosed, or who has in mind the number which is to be found and disclosed, indicates or states which group or column or columns of the correlated numerically distinguished or numerically related groups contain the number so selected and which is to be found or ascertained and disclosed by the operator, by or with the aid of the mechanical means herein described. And numbers corresponding with or representing the groups or columns in which such number or numbers so to be found and disclosed are contained, are added together and presented and exposed in reading position upon the computing wheel or wheels, by turning such wheel or wheels containing the number or containing numbers which are components of the selected number, and which, when added together will produce the selected number or numbers.

For example, if one's age appears in groups or columns "A", "C", "D" and "E", the numerical relation or positions, or the group-distinguishing title numbers of which columns would be 1, 3, and 4 in the series of four columns lettered "A", "B", "C" and "D", in the order of their numerical arrangement or relative positions, the numbers 1, 3 and 4, are added together by turning the "units" computing wheel 7 one notch or number, thus bringing the figure 1 to reading position within the opening 28, then turning said wheel three notches or numbers, for column 3, thereby adding 3 to 1, making 4 which is presented in reading position on wheel 7 within the opening 28, then turning

said wheel 7 four notches or numbers, to add 4, making 8, and causing the figure 8 to be presented in reading position on said units wheel in opening 28. The "tens" wheel 8 is then turned 1 notch or number, for the group or column lettered "E", which is group or column 1 of the series of four columns "E", "F", "G", and "H", corresponding group-distinguishing numbers for which are arranged in numerical order on said "tens" wheel, as already described, thus bringing the digit 1 on the "tens" wheel to reading position within the opening 28. The number, which in this instance is a "two-digit" number, thus found and displayed in reading position, is "18". And "18" is the selected number, or number representing the age to be found and disclosed.

In turning the computing wheels the finger of the operator is placed in the proper peripheral notch on the wheel or wheels 7 and 8 the notches being indicated by the adjacent graduation marks and letters, and the wheel is turned until the movement of the finger and of the wheel is stopped by an adjacent stationary notch 15 or 16, as the case may be, on the edge of the tablet, the initial positions of the wheels 7 and 8 being, of course, with "O" on each wheel in reading position.

If one's age, or the selected number to be found and disclosed is in groups or columns "B", "C", "D", "F" and "G", the age or selected number is "59", and is found and disclosed by the operation of the device as above described. The directions for the operation of the device are printed on the front leaf 2 of the tablet 1 in space 29, or in any place suitable for the purpose. And a space 30 is provided on the back leaf 3, for containing advertising matter, or other printed matter, or pictures of or relating to things to be advertised, or for containing anything which is to be displayed thereon. The sheet 1 provides both inner and outer surfaces 110 which may contain printed or other matter; and the margin 4 may be cut to separate the front and back leaves 2 and 3 along that margin, if desired, the leaves being held together by the eyelets 6.

I claim:

1. In a device of the class described, the combination of a tablet provided with a series of correlated groups of numbers, each of said groups being provided with a group-distinguishing mark, a rotative computing member mounted on said tablet and provided with a series of numbers on and movable with said rotative member, peripheral notches on the rotative member adjacent to said movable numbers and equally spaced apart, and graduation marks on the tablet and corresponding with said group-distinguishing marks, said graduation marks being equally spaced apart and each being nor-

mally adjacent to a predetermined notch and corresponding number on said rotative member.

2. In a device of the class described, the combination of a tablet provided with a series of correlated groups of numbers, said groups being provided with group-distinguishing characters indicating the numerical relation of the groups, a rotative computing member mounted on said tablet and provided with a series of numbers arranged in numerical order corresponding with the numerical relation of said correlated groups and equally spaced apart on said rotative member, and graduation marks on the tablet and adjacent to said movable numbers on said rotative member, and equally spaced apart, each of said graduation marks being related to a corresponding group-distinguishing character and acting to indicate the extent of movement of the rotative member required to cause a corresponding number on said rotative member to move from normal initial position to reading position.
3. In a device of the class described, the combination of a tablet provided with a series of correlated groups of numbers, a rotative member mounted on said tablet and provided with a series of numbers thereon comprising the ten digits arranged in consecutive numerical order and equally spaced apart, peripheral notches on the rotative member comprising a notch for each of said digits respectively, said notches being equally spaced apart, and graduation marks on the tablet adjacent to the notched peripheral margin of said rotative member and equally spaced apart, said graduation marks representing corresponding correlated groups of numbers in said series of groups and indicating the notches to be engaged in the operation of turning the rotative member to move predetermined numbers thereon in predetermined order, and means on the tablet for indicating the reading position for the numbers on the rotative member.
4. In a device of the class described, the combination of a tablet provided with a series of correlated groups of numbers, a rotative computing member mounted on said tablet and provided with a series of numbers thereon comprising the ten digits arranged in consecutive numerical order and equally spaced apart, peripheral notches on said rotative member comprising a notch for each of said numbers respectively, said notches
- being equally spaced apart and adapted to be engaged by the operator in the operation of turning the rotative member to move a predetermined number thereon to reading position, graduation marks on the tablet adjacent to the notched peripheral margin of said rotative member and equally spaced apart, said marks representing corresponding related groups of numbers in said series of groups, means on the tablet for indicating the reading position of numbers on the rotative member, and means for stopping the rotative member in position to present a predetermined number thereon in reading position.
5. In a device of the class described, the combination of a tablet provided with a series of numerically correlated groups or columns of numbers thereon, and a plurality of rotative computing members mounted on said tablet, each of said rotative members having a series of numbers thereon comprising the ten digits arranged in successive numerical order, each of said digits being movable to and adapted to be stopped in reading position selectively, for finding and disclosing a number identical with any predetermined corresponding selected number contained in said series of correlated groups of numbers.
6. In a device of the class described, the combination of a tablet provided with a series of numerically related groups or columns of numbers thereon, a plurality of rotative members mounted on said tablet, each of said rotative members having a series of numbers thereon comprising the ten digits arranged in numerical order, said digits being movable with the rotative members on which they are contained to reading position and adapted to be stopped in reading position selectively, for finding and disclosing predetermined selected numbers which are identical with predetermined corresponding selected numbers contained in said series of correlated groups of numbers, means for indicating the reading positions for numbers contained on said rotative members, and means for stopping said rotative members in position to present any predetermined selected numbers thereon in reading position.

Signed at Chicago, in the county of Cook and State of Illinois this 31st day of July, 1926.

ERNEST C. DES ENFANTS.
